BEACH ACCESSORY

Clifford E. Julian, Fort Lauderdale, Fla.

Application November 5, 1938, Serial No. 239,141

15 Claims. (Cl. 135—5)

The present invention relates to a beach accessory adapted for use as a sunshade, backrest and/or combined mat and sunshade.

A primary object of the invention is to provide a beach accessory of simple construction which may be conveniently set up for use as a mat, backrest and/or sunshade and which may be readily folded into a convenient package for transportation or storage.

10 Another object of the invention is to provide a beach accessory adapted for use as a mat, backrest, and/or sunshade in the form of a flexible unit comprising a length of flexible material and shape maintaining flexible frame members carried thereby which may be flexed to dispose a portion of said unit in any one of a plurality of selected positions with relation to another portion thereof.

20 A further object is to provide a flexible unit comprising a length of fabric and flexible form retaining frame members attached thereto which may be set up with one end portion lying flat on the ground and with the other end arched to a selected one of various positions overlying the ground engaging portion to provide a combination reclining mat and canopy.

25 Other objects and advantages of the invention will become apparent from the following detailed description of the invention and upon reference to the accompanying drawings, in which,

30 Figure 1 is a perspective view of a preferred embodiment of the invention set up in one selected form.

35 Figures 2 to 6 inclusive are diagrammatic views illustrating other ways of setting the unit up.

Figure 7 is a plan view of the unit laid out flat and with the end supports detached.

40 Figure 8 is a fragmentary view, partially in section, showing the manner of mounting the flexible frame members on the fabric section.

45 Figure 9 is an edge view of part of a frame member.

Figure 10 is an enlarged perspective view showing a joint between sections of the frame members.

50 Figure 11 is a perspective view of a supporting stake.

Figure 12 is a perspective view of a spacer bar.

55 Figure 13 is a transverse sectional view illustrating the manner of mounting a spacer bar between the frame members.

Figures 14 to 18 are diagrammatic views illustrating the steps of folding the unit into a package for transportation and storage.

55 Referring more particularly to the drawings, as

seen in Figure 7, the flexible unit comprises a section of flexible material 20 which is preferably a rectangular piece of canvas or other suitable fabric. The opposite longitudinal edges of the section 20 are hemmed as at 21 to provide pockets 22 for the reception of elongated flexible frame members 23.

The frame members 23, which are preferably in the form of flat spring steel strips, are at least as long as the fabric section 20 and are provided at one end with loops or eyes 24. The loops 24 provide a convenient means for detachably connecting one end of each of the frame members to the upper ends of stakes 25, which are provided with snap hooks 26 for engaging the loops 24.

The flexible frame members 23 each have an overall length of about twelve feet and are made up of three sections of spring steel strip about four feet long hinged together end to end so as to break in one direction only. The steel strips are about $\frac{3}{4}$ " wide by $\frac{1}{16}$ " thick. The hinge connection 27 between two adjacent frame sections 28 and 29 is shown in detail in Figure 10. The strips are provided at their ends with hinge eyes 30 and are connected by a pintle pin 31. The frame sections are provided with stops 32 on the back thereof, immediately adjacent the hinge eyes 30, which abut one another to prevent pivotal motion between the sections in one direction.

Due to the stop hinge connections between the frame sections, the frame member may be flexed in the manner of a single unitary strip in one direction and the ends may be folded back on the middle section in the other direction.

The stakes 25, which support one end of the unit, are adjustable in length, being formed of two telescoping sections 32 and 33. The outer and lower sleeve section 32 has a thumb screw 34 threaded through the wall thereof adjacent its upper end to engage the inner section 33 to lock the sections together when adjusted to the stake length desired. The lower end of the sleeve 32 is pointed to enter the ground and is provided with a foot plate 35, spaced from the pointed end thereof, to aid in inserting the stake in the sand when setting up the unit.

A cross piece or frame member 36, which may be of wood or any other suitable material, as shown in Fig. 12, is provided to hold the side frames in properly spaced relation when the device is in use. The cross piece is provided with grooves 37 in each end to receive the edges of the frame members 23 as seen in Figure 13, and

is substantially equal in length to the width of fabric between the frame members.

In setting up the device for use, the fabric section, with the side frame members 23 disposed 5 in the pockets at opposite sides thereof, is laid flat upon the ground with the hinge stops 31 facing up. The stakes 25 are then connected to the side frames by snapping the hooks 26 on the loops 24. The end 39 of the unit with the stakes 10 attached is then raised and doubled back over the portion 40 still lying flat on the ground to the extent desired and the stakes, adjusted to the proper length, are inserted in the ground. The cross frame member 36 is then placed in position 15 to separate the frame members and hold them spaced apart with the fabric tautened therebetween as seen in Figure 13. The device is then ready for use as a combined mat and canopy or sunshade.

20 By adjusting the length and inclination of the stakes and the amount of overhang of the doubled over end 39 of the unit, various effects may be obtained as seen in Figures 1, 2, 4 and 5. In these illustrations, it will be seen that innumerable variations between the relative sizes of the canopy and mat portions 39 and 40, respectively, 25 may be attained as desired.

If no canopy or sunshade is desired, the unit 30 may be used as a combined mat and backrest, as seen in Figure 6. When thus used, one end is merely supported in elevated position by the stakes 25 to form a backrest 41 at the end of a mat portion 42.

If a large canopy without a mat is desired, the 35 ends 43 of each of the frame members 23, opposite the loops 24, are exposed by drawing back the fabric at this point and are inserted in the ground. The unit is then flexed in the form of an arch with the other end 43 supported by the stakes as seen in Fig. 3.

40 The steps of folding the unit are shown in Figs. 14 to 18. When the unit is to be taken down, the cross frame member 36 is removed and the stakes are disconnected from the loops 24. 45 Due to the tendency of the frame members to straighten, the unit will automatically return to its original position flat on the ground, as seen in Figure 14. The sides are then folded inwardly, as seen at 45 in Figure 15, to reverse the position 50 of the stop hinges of the frame members. The ends 46 and 47 of the partially folded unit are then folded inwardly onto the center section 48 as seen in Figures 16 and 17 and the pad thus formed is rolled up into a compact package 49 55 as seen in Figure 18.

55 When folded and rolled up in this manner, the unit makes a roll about four feet long. The sections of the stakes 25 are about four feet long and they can thus be carried rolled up in the bundle. The cross bar 36 is preferably the same 60 length as one of the sections of the frame so that it also may be rolled up in the bundle. In cases where the unit is to be made wider than the length of one of the frame sections, the cross frame member will be jointed to fold in half.

65 While a preferred embodiment of the invention and manners of using the same have been shown and described by way of illustration, it will be understood that various modifications in the 70 details of construction of and manner of using the invention, may be resorted to without departing from the spirit of the invention within the scope of the appended claims.

I claim:

75 1. In a beach accessory of the character de-

scribed, a flexible self-contained unit adapted to be bent intermediate its ends to dispose one end portion in any one of a plurality of selected positions overlying or upstanding with relation to the other end portion disposed on the ground, said unit comprising a substantially rectangular section of fabric, resiliently flexible side frame members carried by said fabric section in laterally spaced relation with respect to each other, and ground engaging means detachably secured to 10 one end of said unit for maintaining the adjacent end portion thereof in a selected elevated position with respect to the other end portion thereof.

2. A self-supporting beach accessory adapted 15 for use as a mat, backrest and/or sunshade, comprising a substantially rectangular fabric section, resiliently flexible side frame members mounted at opposite longitudinal edges of said fabric section, and ground engaging supporting means connected to one end of said resilient side frame members.

3. In a beach accessory adapted for use as a mat, backrest and/or sunshade, a flexible unit 20 comprising a length of flexible material and shape maintaining resiliently flexible side frame members carried thereby, whereby said unit may be flexed in the direction of its length to dispose one end portion thereof in any one of a plurality of selected elevated positions with relation to 25 the other end portion thereof, and ground engaging means for maintaining said first mentioned end portion in a selected elevated position.

4. In a beach accessory of the character de- 35 scribed, a flexible self-contained unit comprising a section of fabric and form retaining resiliently flexible side frame members carried by said fabric section in laterally spaced relation, and elongated ground engaging elements detachably 40 connected to one end of said frame members.

5. A self-contained, self-supporting beach ac- 45 ccessory adapted for use as a mat, backrest and/or sunshade, comprising a fabric section, resiliently flexible side frame members secured to opposite longitudinal edges of said fabric section, and ground engaging supporting means connected to one end of said side frame members.

6. A self-contained, self-supporting beach ac- 50 ccessory comprising a substantially rectangular fabric section, resiliently flexible side frame members secured to opposite longitudinal edges of said fabric section, a cross member intermediate the ends of said unit for maintaining said side frame members in spaced relation, and ground 55 engaging supporting means connected to one end of said side frame members.

7. A self-contained, self-supporting beach ac- 60 ccessory comprising a substantially rectangular section of fabric, resilient side frame members secured to opposite longitudinal edges of said fabric section, a stretcher member maintaining said side frame members in spaced relation, and stake members connected to one end of each of said side frame members.

8. A beach accessory comprising a substantial- 70 ly rectangular section of fabric, resilient side frame members secured to opposite longitudinal edges of said fabric section, a stretcher member maintaining said side frame members in spaced relation, and a stake member connected to one end of each of said side frame members, whereby with one end of said fabric and resilient frame members engaging the ground, the other end thereof may be supported by said stakes.

in any one of a plurality of elevated positions with respect thereto.

9. A beach accessory comprising a substantially rectangular section of fabric, resiliently flexible side frame members secured to opposite longitudinal edges of said fabric section, a stretcher frame member maintaining said side frame members in spaced relation, and an elongated stake member connected to one end of each of said side frame members, whereby, with one end of said fabric and resilient frame members engaging the ground, the other end thereof may be looped upon itself and supported by said stake members in any one of a plurality of positions overlying the ground engaging portion thereof.

10. In a beach accessory of the character described, a flexible unit comprising a substantially rectangular fabric section, resiliently flexible shape-maintaining and supporting side frame members secured to opposite longitudinal edges of said fabric section, and ground engaging supporting means connected to one end of said unit.

11. In a beach accessory of the character described, a flexible unit comprising a substantially rectangular fabric section, resiliently flexible shape-maintaining and supporting side frame members secured to opposite longitudinal edges of said fabric section, and ground engaging supporting means connected to one end of said unit, whereby, with the other end of said unit engaging the ground, the unit may be flexed intermediate its ends to dispose the first mentioned end thereof in any one of a plurality of elevated positions with respect to the ground, said ground engaging supporting means serving to maintain the elevated end of said unit in the selected position.

12. In a beach accessory of the character described, a fabric section, resiliently flexible shape-maintaining and supporting side frame members secured to opposite longitudinal edges of said fabric section, and stake members connected at their upper ends to one end of said frame members, said stakes being adjustable in length to support said ends of said frame members at various elevations and positions with respect to the other end thereof.

13. In a beach accessory of the character described, a flexible unit comprising a substantially rectangular fabric section, flexible side frame

members coextensive with said fabric section carried at opposite longitudinal edges thereof, said side frame members each comprising a plurality of flexible strips, stop hinge connections between said strips, whereby said frame members may be flexed in one direction to dispose one end portion of said unit in any one of a plurality of selected positions with relation to the other end portion thereof and folded back upon themselves in the other direction to permit folding of said unit into a compact package, and ground engaging supporting means connected to the first mentioned end portion of said unit.

14. In a beach accessory adapted for use as a mat, backrest and/or sunshade, a flexible unit comprising a length of flexible material and longitudinally extending shape maintaining flexible frame members carried thereby, said frame members each comprising a plurality of flexible strips and stop hinge connections between said strips, whereby said frame members may be flexed in one direction to dispose one end portion of said unit in any one of a plurality of selected positions with relation to the other end portion thereof and folded back upon themselves in the other direction to permit folding of said unit into a compact package, and stake members connected to the first mentioned end portion of said unit, said stake members being adjustable in length to support said end portion at various elevations.

15. In a beach accessory of the character described, a flexible unit comprising a rectangular fabric section, longitudinally extending shape maintaining flexible frame members carried at opposite edges of said fabric section, said frame members each comprising a plurality of spring metal strips, stop hinge connections between adjacent ends of said strips whereby said frame members may be flexed as a unit in one direction to dispose one end portion of said unit in any one of a plurality of raised positions with relation to the other end portion thereof and folded back upon themselves in the other direction to permit folding of said unit into a compact package, and stake members detachably connected to the raised ends of said frame members for retaining the latter in the desired raised position.

CLIFFORD E. JULIAN. 50
